UNITED STATES PATENT OFFICE.

RICHARD A. BOOKER, OF RICHMOND, INDIANA.

ELECTRIC PEENING MACHINE.

Application filed April 29, 1922. Serial No. 557,472.

To all whom it may concern:

Be it known that I, RICHARD A. BOOKER, a citizen of the United States, residing at Richmond, in the county of Wayne and State of Indiana, have invented new and useful Improvements in Electric Peening Machines, of which the following is a specification.

The present invention relates to hammering or peening machines for hammering piston rings.

While intended particularly for peening piston rings, it will be understood that it might be adapted to uses other than the specific use herein shown.

It has for its object to provide a machine in which the peening operation may be rapidly and accurately performed; in which the blows of the peening device upon the ring are automatically and accurately graduated, and which provides for striking a given number of blows.

It is now customary to hammer or peen piston rings on their inner peripheries in order to give the proper set and uniform tension, so far as this can be accomplished, to the ring throughout its circumferential length, and it has been proposed to secure this set and uniform tension by graduating or varying the density of the metal of the ring in certain portions thereof. Under the present practice, the blows are heaviest and the density greatest at a point opposite the ends of the ring, these rings, in order that they may expand and contract, being split or cut at one point in their circumferential length. Theoretically, by making the heaviest blows and giving the greatest density to the ring at the point opposite this cut, the tension of the ring is made more uniform, and it has been proposed to graduate the peening blows in each direction from this point of greater density opposite the cut in the ring, the blows, and consequently the density of the ring, gradually decreasing as they approach the end of the ring.

Various expedients have been adopted for securing this graduated peening of the ring, and my present development is an improvement on the device now known to me for accomplishing this.

Briefly, I accomplish this result by a novel mechanism in which, in addition to other features of novelty which will be hereinafter more fully set forth, I have provided means for automatically controlling the blow of

the peening tool, such means being an electrically controlled hammer or equivalent device, the blows of which, as the peening operation proceeds, are varied by means of a resistance which is automatically increased and decreased as the work proceeds, and the blows of the peening tool correspondingly controlled and graduated; and finally provision is made when desired for striking a given number of blows during the revolution of the ring which is being peened.

In order that the invention may be clear to those skilled in the art, I have shown in the accompanying drawings one embodiment thereof, this embodiment being merely illustrative, and not restrictive, so far as mechanical make-up and details are concerned, of my invention.

In the drawings:—

Fig. 1 is a view in front elevation of a peening machine constructed in accordance with my invention.

Fig. 2 is an end view looking from the right in Fig. 1.

Fig. 3 is a vertical sectional view substantially on the line 3—3 of Fig. 1.

Fig. 4 is a top plan view of the machine.

Fig. 5 is a diagrammatic view to show the magnet circuit and the resistance which controls the action of the peening tool.

Fig. 6 is a sectional view of a make and break device suitable for controlling the number of blows given to the ring.

Referring to the drawings by numbers, like numbers indicating like parts in the several views, 10 indicates the base of the machine, which may be of any suitable construction. Mounted in said base is a drive shaft 11 provided with a driving sprocket 12, a fixed clutch member 13 and a movable clutch member 14 suitably splined to the shaft 11 and provided with a clutch operating mechanism which will be later described.

The shaft 11 is provided with a worm gear or equivalent driving element 15 which meshes with a ring gear 16 mounted in a suitable frame 17 carried by the base 10, the frame 17 being so formed as to provide a bearing member in which the ring gear 16 rotates.

The ring gear 16, as shown in Fig. 3, is provided centrally with an orifice 18, here shown as of circular form, although, obviously, that is a matter of design; the orifice 18 in the present instance having an in-

clined wall adapted to receive an anvil member 19 which may be removably mounted therein, and secured either by positive engagement with the bore or by any suitable securing means. The anvil ring 19 is also provided with a central bore 20, which bore terminates in a ring-like abutment 21 forming a seat for the piston ring 22 which is to be peened.

10 The mechanism just described serves as the rotating instrumentality for advancing the piston ring. Upon rotation of the shaft 11 the worm 15 will drive the gear ring 16 with the anvil 19 and the ring 22 carried thereby through a circumferential path so as to present different portions of the periphery of the ring for peening.

15 The anvil 19, as shown in Fig. 3, is open centrally so as to give a working space for the peening tool, which is shown, in this particular instance, as operating from the side of the anvil opposite that in which the ring is placed in its seat. The peening mechanism comprises the hammer or peening tool 23 which, as shown in the present instance, comprises a body portion and a hammer head having any suitably designed peening point 24. The peening tool 23 is pivotally mounted on suitable supports 25 mounted upon the base 10 of the machine, and at its forward end is provided with an adjustable spring 26, the upper end of which is coupled to an arm 27 secured at its rear end to the support 25 and projecting 30 forwardly, as shown in Figs. 2 and 3, so that there is a tendency always to maintain the peening tool 23 in raised position.

20 The peening tool 23 carries an armature 28 below which is disposed electromagnetic means, here shown as two electromagnets 29, which, when energized, will attract the armature 28 carried by the peening tool 23. In the present development the armature 28 is shown as lying transversely of the tool 23 with the electromagnets 29 disposed on either side of the tool 23, there being clearance enough between the magnets for the tool 23 to operate, this giving a very compact and practical arrangement, although it 25 will be understood that different arrangements of parts may be made.

25 It will be seen that with this arrangement of members the magnets 29, upon energization from a suitable source of current, will attract the armature 28 and pull the peening tool 23 down against the resistance of its spring 26, giving a sharp peening blow to the ring 22, which ring is, of course, traveling with the constantly rotating gear ring 16 and anvil 19, and at a speed which can, of course, be determined by the ratio of the driving gears and in accordance with the needs of the work.

30 The energization of the magnets 29 will be controlled by a make and break device

comprising a spring supported bar 30 which carries an adjustable tailpiece 31 projecting through an opening in the member 27, and provided with a nut at its outer end to limit the stroke or movement of this make and break member 30, the spring 32 tending to normally maintain the parts in the position shown in Figs. 2 and 3.

35 With this arrangement of parts it will be understood that the current from suitable leads (not shown) passes to the magnets through the make and break device, the armature 28 being normally held in raised position and in contact with the bar 30. Upon energization of the magnets 29 by the passage of current, the armature 28, together with the hammer or peening tool 23 will be thrown down against the tension of the spring 26; strike its blow on the ring 22, and this downward movement will break the circuit between the armature 28 and the bar 30, deenergizing, momentarily, the magnets 29 and permitting the spring 26 to return the parts to starting position, thereby closing the circuit and repeating the energization of the magnets. The mounting of the make and break device 30 on the spring 32 in the manner shown serves to cushion the return stroke of the armature after the peening blow, and prevents any sudden stop of the tool 23 on its return stroke. The adjustability of the make and break bar 30 permits adjustment of the gap between said bar and the armature, and by disposing the proximate surfaces of the bar 30 and the armature on an incline to the horizontal, as shown, a smooth sliding mechanical contact occurs without any abrupt hammering blow between the parts. The spring 26 is of such tension, which tension may be adjusted by the threaded bolt and nut connection of the spring with the bar 27, as that, while it will return the moving parts with proper speed, it will not interfere, materially, with the effectiveness of the peening tool.

40 From the foregoing it will be seen that the peening tool and its associated moving armature parts are spring mounted in both directions so that a smooth mechanical operation results.

45 As has been heretofore stated, it is customary, in peening piston rings, to graduate the intensity of the blows preferably from a point on the inner periphery of the ring in opposite directions with gradually decreasing force. This has been accomplished heretofore, so as far as the art is now known to me, by varying the length of stroke of the peening tool, which involves more or less complicated mechanical instrumentalities, and increases, materially, the structural parts of the machine.

50 In the present development I accomplish this result without altering the length of

stroke of the peening tool, and am able to very closely and uniformly graduate the blow. This result is obtained by providing the magnet circuit with a resistance box or rheostat element 33, the arrangement of magnet circuit, rheostat, and make and break device being diagrammatically shown in Fig. 5.

The variable resistance 33 will have any usual or desired resistance elements arranged in the circuit and so disposed as to be cut in by the rheostat controller 34 sweeping over the contact points 35, which control the resistance elements 33.

16 While various mechanical devices may be employed for giving the proper throw to the controller 34, one satisfactory construction is that shown herein, in which the said control arm 34 is mounted upon 20 a rock shaft 36 arranged in suitable bearings on the frame, and preferably disposed so as to project between the magnet spools 29, said rock shaft having at its forward end the crank arm 37. The said crank arm 25 37 engages a cam 38 carried by the rotating ring gear 16, said cam being suitably plotted so as to give a movement to the crank arm, rock shaft and control arm 34, which controls the resistance elements in the 30 resistance box 33. A spring 33' is provided which will return the control arm 34 to starting position as the cam 38 revolves, said spring being adjustably connected with any suitable arm 34' secured to the frame of 35 the machine.

These resistances may, of course, be arranged for any sequence of blows, but in the present illustrated example, the arrangement of resistance elements will be such as that the control arm 34 cuts the resistance elements in and out to graduate the peening blows in both directions from a center opposite the split in the piston ring where the heaviest blow will be made, 45 with gradually decreasing blows on either side of this central blow. To illustrate from the diagram shown in Fig. 5, it will be seen that in that position the resistance elements 33 are all cut in to circuit and the peening blow struck under this condition of the parts will be the lightest blow because of the cutting down to the minimum of the current passing to the magnet 29. As the control arm 34 is moved by the cam 50 38 it will be cut out step by step the resistance elements 33 until the end of the series is reached and the resistance is at its minimum with a consequent maximum current to the magnet 29, resulting in the heaviest blow of the peening tool. The control arm 55 34 will, in the continued operation of the machine, again sweep back over the control point of the resistance 33, gradually cutting in the resistance elements until it has returned to the position shown in Fig. 5,

namely, to the point where the blow is at its lightest.

This is merely one illustration, and it will be clear that the resistances and the control may be so disposed and manipulated 70 as that any desired sequence of blows can be provided for.

In order that, if desired, provision may be made to insure the striking of a given number of blows the shaft 11 may be provided at its end with a make and break device to control current flow to the magnets 29 so as to energize them at regular intervals during the rotation of the gearing which carries the piston ring being operated on. While this make and break device may take various forms, it is here shown as a hub 39 attached to the end of the shaft 11, although, of course, it could be mounted at any suitable point on the shaft 11. The hub 39 is stepped in the construction herein shown and is formed of insulating material or of such construction as to insulate it, the smaller portion, as here shown, having a conducting band 40 and the larger portion having inserts 41 of conducting material in circuit, by any suitable connections, with the conducting band 40. The inserts 41 may be in such number as may be desired so that for a given number of revolutions of the shaft 11 there will be a given number of energizations of the magnets 29. Resting upon the portions of the hub will be the conducting members or brushes in circuit as shown in the diagram of Figure 5 with any suitable source of electricity so that as the shaft 11 and this make and break attachment revolves the circuit through the resistance box and the magnets will be opened and closed at uniform intervals at such periods of time as may be determined by the number of inserts 41 in the larger section of the hub 39, it being understood that provision will be made whereby the areas between the inserts 41 are insulated 90 so as to break the circuit.

It is desirable that an automatic stop mechanism be provided which will throw out the driving mechanism at a predetermined time, and one convenient form of stop mechanism, as herein illustrated, comprises the clutch controlling lever 42 pivotally mounted on a suitable support on the frame and projecting through a suitable aperture in the housing 17 so that its toe 43 engages the shoulder 44 of the ring gear 16, as shown in Fig. 1. The said ring gear has, at the appropriate point in its shoulder, a toe engaging recess 45, this being so located as that the toe 43 of the clutch shift lever 42 will drop into said recess at the end of the peening operation, this movement of the lever 42, which is engaged at its opposite end with the shiftable clutch member 14, unshipping the clutch and bringing the shaft 115 120 125 130

15 to a stop. The said stop lever 42 is provided with a handle 46, by means of which the toe 43 may be thrown out of the recess 45 and the clutch parts reengaged to start 5 the machine. The lever 42 will be so adjusted as to weight that its toe 43 will overbalance the clutch parts, so that the toe 43 will always rest on the shoulder of the surface 44 of the ring gear 16 and drop into 10 the recess 45. If desired, this result can be accomplished by equivalent means, such as a spring tending always to hold the toe 43 or shoulder 44.

From the foregoing it will be seen that a 15 very compact, easily controlled and regulated and efficient mechanism is provided for peening piston rings.

While I have described a specific mechanical construction, and that the best now 20 known to me, it will be obvious that equivalent mechanical elements other than those shown may be adopted to attain the results accomplished by the illustrated example here given without departing from the 25 range of my invention.

I claim:

1. In a machine of the class described, the combination of a work-holder, a peening tool in operative relation to the work in said 30 holder, an electro-magnet to actuate and effect a peening blow of said tool, and automatically operable means for controlling current flow in said magnet to vary its actuating pull on and graduate the blow of said 35 tool.

2. In a machine of the class described, the combination of a travelling work-holder, a peening tool having a constant length of stroke in operative relation to the work in 40 said holder, an electro-magnet to actuate and effect a peening blow of said tool, and automatic means controlled by a moving part of the machine to control current flow in said magnet to vary its actuating pull on and progressively graduate the blow of said 45 tool on the work in said travelling work-holder.

3. In a machine of the class described, the combination of a travelling work holder, a 50 peening tool having a constant length of stroke in operative relation to the work in said holder, an electro-magnet to actuate and effect a peening blow of said tool, and means controlled by said moving work holder automatically to vary the current flow in 55 said magnet and progressively graduate its actuating pull on and the blow of said tool on the work in said travelling work holder.

4. In a machine of the class described, the combination of a rotating work-holder, a 60 peening tool having a constant length of stroke operative on the work at a predetermined point in the path of rotation of said 65 holder, an electro-magnet to actuate and ef-

fect a peening blow of said tool, and means controlled by said rotating work-holder automatically to vary the current flow in said magnet and progressively graduate its actuating pull on and the blow of said tool 70 on the work in said rotating work-holder.

5. In a machine of the class described, the combination of a rotating work holding ring, a peening tool having a constant length of stroke projecting into the bore of said ring and operative on the work therein at a predetermined point in the path of rotation of said work holder, an electro-magnet adjacent said work holder and in operative relation to said tool to actuate and effect a 80 peening blow of said tool, a variable resistance in the circuit of said magnet, and means actuated by said rotating work holder automatically to vary said resistance and the current flow in said magnet and progressively graduate its actuating pull and the blow of the work holder on the work in 85 said rotating work holder.

6. In a machine of the class described, the combination of a rotating work holder, a 90 peening tool having a constant length of stroke operative on the work at a predetermined point in the path of rotation of said holder, means tending normally to maintain said tool at the upper end of its stroke, an electro-magnet in operative relation to said tool to actuate and effect a peening blow thereof, and circuit interrupting means controlled by said tool. 95

7. In a machine of the class described, the combination of a rotating work holder, a 100 peening tool having a constant length of stroke operative on the work at a predetermined point in the path of rotation of said holder, means tending normally to maintain said tool at the upper end of its stroke, an electro-magnet in operative relation to said tool to actuate and effect a peening blow thereof, circuit interrupting means controlled by said tool, a variable resistance actuated by said rotating work holder automatically to vary the current flow in 105 said magnet and progressively graduate its actuating pull on and the blow of said tool on the work in said rotating work holder. 110

8. In a machine of the class described, the combination of a rotating work holder, a 115 spring peening tool in operative relation to the work in said holder, an electro-magnet to actuate said tool against the action of its spring and effect a peening blow, a variable resistance in the circuit of said magnet, means for controlling said variable resistance automatically to vary the current flow in said magnet, and a cam on said rotating work holder to actuate said resistance controlling means. 120

9. In a machine of the class described, the combination of a rotating work holding ring, a spring peening tool projecting into 130

- the bore of said ring in operative relation to the work therein, an electro-magnet adjacent said ring, an armature on said tool in the field of said magnet, circuit interrupting means carried by said tool, a variable resistance in the circuit, a controller for said variable resistance, a rock shaft for actuating said controller, and a cam on said ring to operate said rock shaft.
10. In a machine of the class described, the combination of a rotating work holding ring, a spring peening tool projecting into the bore of said ring in operative relation to the work therein, an electro-magnet adjacent said tool, an armature on said tool in the field of said magnet, circuit interrupting means carried by said armature, a variable resistance in the circuit, a crank shaft having a resistance controlling arm thereon, and a cam on said ring engaging said crank shaft.
11. In a machine of the class described, the combination of a suitable base, a gear ring support on said base, a gear ring mounted in said support, means for continuously driving said gear ring, a spring peening tool projecting into the bore of said ring in operative relation to the work therein, an electro-magnet with its bobbins disposed on either side of said tool, an armature lying transversely of said tool in the field of said electro-magnet, circuit interrupting means carried by said tool, a variable resistance in the circuit, an oscillating arm controlling said resistance, a crank shaft to actuate said arm, and a cam on said ring to actuate said crank arm.
12. In a machine of the class described, the combination of a suitable base, a ring support on said base, a work holding ring mounted in said support, means for continuously driving said ring, a peening tool projecting into the bore of said ring in operative relation to the work therein, an adjustable spring normally to maintain said tool at the upper end of its stroke, an electro-magnet having its bobbins disposed on either side of said tool, an armature disposed transversely of said tool in the field of said magnet, adjustable circuit interrupting means controlled by said armature, a variable resistance in the magnet circuit, an oscillating controller for said resistance, a crank arm for moving said controller, and a cam on said ring to actuate said crank arm.
13. In a machine of the class described, the combination of a rotating work holding ring, a spring peening tool projecting into the bore thereof in operative relation to the work, an electro-magnet adjacent said tool, an armature carried in the field of said magnet carried by said tool, and a circuit interrupter having an inclined contact face carried by said armature.
14. In a machine of the class described,
- the combination of a base, a ring support mounted thereon, a rotatable work holding ring mounted in said ring support, a ring driving shaft to continuously rotate said ring, clutch mechanism on said shaft, a clutch operating lever connected at one end to said driving shaft and its opposite end provided with a tripping toe engaging the periphery of said rotating ring, and means at a predetermined point of the periphery of said ring to trip said lever and clutch mechanism and stop rotation of said shaft and ring.
15. In a machine of the class described, the combination of a base, a ring support mounted thereon, a rotating work holding gear ring mounted in said support, a worm shaft to drive said gear ring, clutch mechanism on said shaft, a clutch tripping lever projecting through said support having one end thereof engaging with the periphery of said ring and its opposite end connected to said worm shaft, and a tripping recess in the periphery of said ring to trip said lever and clutch mechanism and stop rotation of said shaft and ring at a predetermined point.
16. In a machine of the class described, the combination of a movable work holder, means for moving said work holder, a peening tool in operative relation to said holder and work thereon, an electro-magnet for actuating said tool, a source of energy for said magnet, and a circuit interrupter to make and break circuit to said magnet at predetermined intervals.
17. In a machine of the class described, the combination of a movable work holder, means for moving said work holder, a peening tool in operative relation to said holder and work thereon, an electro-magnet for actuating said tool, a source of energy for said magnet, and a circuit interrupter actuated by the work holder moving means to make and break circuit of said magnet at predetermined intervals.
18. In a machine of the class described, the combination of a movable work holder, means for moving said work holder through a predetermined path, a peening tool in operative relation to said holder and work thereon, an electro-magnet for actuating said tool, a source of energy for said magnet, and a circuit interrupter actuated by said work holder moving means to make and break circuit to said magnet at predetermined intervals during the movement of said work holder.
19. In a machine of the class described, the combination of a rotatable work holder, means for imparting a predetermined angular movement to said work holder, a peening tool in operative relation to said holder and work thereon, an electro-magnet for actuating said tool, a source of energy for

said magnet, and a circuit interrupter rotated by said work holder moving means to make and break circuit to said magnet at predetermined intervals during the angular movement of said work holder.

20. In a machine of the class described, the combination of a rotatable work holding ring, rotatable means for rotating said work holding ring, a peening tool projecting into the bore of said ring in operative relation to work thereon, an electro-magnet for actuating said tool, a source of energy for said magnet, and a circuit interrupter carried by said ring, rotating means to make and break circuit to said magnet at predetermined intervals during the rotation of said ring.

21. In a machine of the class described, the combination of a rotating work holding ring, a rotary shaft for rotating said ring, a peening tool projecting into the bore of

said ring in operative relation to work thereon, an electro-magnet for actuating said tool, a source of energy for said magnet, and a circuit interrupter on said rotary shaft to make and break circuit to said magnet at predetermined intervals during the rotation of said ring.

22. In a machine of the class described, the combination of a movable work holder, means for moving said work holder, a peening tool in operative relation to said holder and work thereon, an electro-magnet for actuating said tool, a source of energy for said magnet, a variable resistance in the magnet circuit, a controller for said variable resistance, and a circuit interrupter to make and break circuit to said magnet at predetermined intervals.

In testimony whereof I have hereunto set my hand.

RICHARD A. BOOKER.
